VENDING MACHINE

Byron A. Babel, Highland, Calif.
Application July 7, 1943, Serial No. 493,767

8 Claims.

The present invention comprehends the provision of a vending machine primarily intended for the sale of tooth brushes, although its general application wherever found desirable is contemplated by the claims.

The invention aims to provide a machine of the character mentioned, which is simple in construction, embodying comparatively few parts, whereby efficiency of operation is assured.

One of the chief objects of the present invention resides in the provision of a novel construction of means for limiting the movement of the brushes incident to the operation of the machine, and successively locating each brush in a position from which it can be readily and easily removed from the machine.

The nature and advantages of the invention will be better understood when the following detail description is read in connection with the accompanying drawings, the invention residing in the construction, combination and arrangements of parts as claimed.

In the drawings forming part of this application, like numerals of reference indicate similar parts in the several views, and wherein:

Figure 1 is a front elevation of the machine embodying the invention.

Figure 2 is an end elevation thereof.

Figure 3 is a fragmentary vertical sectional view.

Figure 4 is an end view with the cover removed.

Figure 5 is a sectional view taken on line 5-5 of Figure 1.

Figure 6 is an enlarged fragmentary detail sectional view.

Referring to the drawings in detail, the machine essentially includes a casing 10 which may be constructed from any suitable material, and also vary in size and configuration without departing from the spirit of the invention. The casing may be of a size to accommodate one or more vending belts of the character illustrated, and to be hereinafter specifically described. The casing can also be supported in any suitable manner, depending upon its size, but the rear wall thereof is preferably provided with openings 11 to receive suitable elements for hanging the machine on a wall or the like.

Arranged within the casing 10 are spaced superimposed brackets 12 and 13 respectively which may be of any desired construction or design. Journaled in these brackets are the shafts 12 and 13 of a pair of driving rollers 14 and 14' respectively. An endless belt 15 of leather or other suitable material is trained over these rollers, and is provided with perforations to accommodate teeth on the rollers in the usual manner. The belt is adapted to support the articles to be

5 vended, which in this specific instance are shown as tooth brushes. The tooth brushes are received by loops on the belt, which can be provided in any suitable manner, preferably by stitching separate pieces or strips of material thereon as shown. Arranged within the casing is a coin receiving receptacle 17.

One end wall 18 of the casing is removable to permit access thereto when necessary, but is normally locked in position. The lower end of the wall 18 is formed with a flange 19 adapted to engage beneath the bottom of the casing and provided with openings to receive pins or studs 20 depending from the casing as shown. The upper end of the wall 18 is equipped with a lock 21, the movable part of which interengages the top of the casing, as illustrated to advantage in Figure 3. Also carried by the wall 18 is a coin controlled device 22 of any conventional form, including a coin receiving channel 23, and a manipulating wheel or disk 24 mounted on the shaft 25. The shaft 25 has associated therewith a clutch sleeve 26 slotted to receive the clutch pin 27 on the shaft 13 for one of the driving rollers as illustrated in Figure 6. Manifestly, by virtue of this construction the end wall 18 can be unlocked and wholly removed from the casing 10 as the occasion might require, during which operation the clutch sleeve 26 slides off the shaft 13.

As hereinabove stated, the machine is primarily intended for vending tooth brushes, and while it is shown and described specifically in this connection, it can be used to vend other articles, and its general application is contemplated by the claims. When used for vending tooth brushes, the handles 28 thereof are positioned in the loops 16 of the belt, with the heads of the brushes, indicated at 29, projecting beyond one side of the belt as illustrated in Figure 5. The brushes are adapted to be singly brought into alignment with an opening in the casing, from which position the head of the brush can be conveniently grasped and removed from the casing through said opening. There are two of such openings indicated at 30, formed in the two adjacent walls of the casing, thus allowing the thumb and finger of the purchaser to be inserted to readily grasp the brush to be removed.

The end wall 18 is provided with an inwardly projecting flange 31 having an offset right angularly disposed terminal portion 32 which is arranged to lie between the belt and the head 29 of each brush as the latter assumes its position for removal from the casing. Also projecting inwardly from the front wall of the casing is a flange 34 disposed in right angular relation to the flange 31 and portion 32, and defining therewith a pocket for the reception of the brush heads, as each brush is brought into alignment with one of the openings 30 for removal. The flange 34 acts

as a stop for the belt, being engaged by the brush heads as they are successively brought into a position for removal, incident to the operation of the belt. Obviously, the right angularly disposed flanges 31 and 34 respectively are stamped from the casing, and thus provide for the openings 30 above referred to.

In practice, a coin of proper denomination is inserted in the coin actuated device 22, which effects a release of the shaft 25 to permit rotation thereof. As the shaft is rotated by the disk 24, the belt is moved in the direction indicated by the arrow in Figures 3 and 4. The next brush in order to be dispensed is thus moved into the pocket defined by the flanges 31, 32 and 34 respectively, striking the flange 34 and thus limiting the movement of the belt. As shown the head of the brush is so located that it can be conveniently grasped and removed from the casing through one of the openings 30 thereof. Carried by the belt is an "Empty" sign, preferably arranged in one of the loops 16 and projecting beyond the side of the belt. When all of the brushes have been vended, this sign 33 is brought into contact with the flange 34 and thus occupies a position where it can be readily seen through the adjacent opening of the casing.

While it is believed that the invention will be readily understood from the foregoing, I desire to have it known that I do not limit myself to what is illustrated, and that such changes may be resorted to when desired as fall within the scope of what is claimed.

What is claimed is:

1. A vending machine including a casing, driving rollers journaled therein one above the other, a vending belt trained over said rollers having means for holding the articles to be singly removed from the machine, means for operating said belt, said casing having an opening through which the articles are singly removed therefrom, and article engaging means for limiting the movement of the belt at each operation thereof to successively position said articles in alignment with said opening.

2. A vending machine including a casing having a removable end wall, spaced superimposed shafts journaled in the casing, driving rollers carried by said shafts, a vending belt trained over said rollers having means for holding the articles to be singly removed from the machine, a coin controlled clutch device carried by said end wall and removably associated with one of said shafts, said casing having an opening through which the articles are singly removed from the casing, and means for limiting the movement of the belt at each operation thereof to successively position said articles in alignment with said opening.

3. A vending machine including a casing, an endless belt movable therein having means for holding the articles to be singly removed from the machine, means for operating the belt, and an article engaging flange projecting inwardly from one wall of the casing, and providing an opening through which the articles are singly removed from the casing, said flange limiting the movement of the belt and successively locating said articles in alignment with said opening.

4. A vending machine including a casing, an endless belt movable therein and having spaced transverse loops adapted to singly receive the articles to be vended, means for operating said

belt, right angularly disposed flanges projecting within the casing from two adjacent walls thereof and defining a pocket adapted to receive a part of each article projecting from one side of the belt, the forming of said flanges resulting in a finger receiving opening in a corner of the casing through which said articles are singly removed from the casing, and one of said flanges being disposed in the path of said articles, and 10 utilized as a stop to successively position said articles in alignment with said opening.

5. A vending machine including a casing, an endless belt movable therein having means for holding the articles to be singly vended, means 15 for operating said belt including a coin controlled clutch device carried by one wall of the casing, said wall being removable to permit access to the casing, said wall also having an opening through which the articles are singly removed from the 20 casing, and an article engaging flange projecting within the casing to limit the movement of the belt and successively position said articles in alignment with said opening.

6. A vending machine including a casing, an 25 endless belt movable therein and having spaced transverse loops adapted to singly receive the handles of tooth brushes, the heads of said brushes projecting beyond one side of the belt and adapted to be grasped for removal of the 30 brushes from the casing, means for operating said belt, said casing having an opening through which said brushes are singly removed therefrom, and a flange projecting within the casing and arranged to be successively engaged by the heads 35 of said brushes, to singly locate the latter in alignment with said opening for removal from the casing.

7. A vending machine including a casing, an 40 endless belt movable therein and having spaced transverse loops adapted to singly receive the handles of tooth brushes, the heads of which project beyond one side of the belt, means for operating said belt, said casing having an opening through which said brushes are singly removed 45 from the casing, means for limiting the movement of the belt and successively positioning the brushes in alignment with said opening, and a flange projecting within the casing and including an offset terminal arranged to occupy a position 50 between each brush head and belt just prior to the removal of the brush from the casing for the purpose specified.

8. A vending machine including a casing, an 55 endless belt movable therein and having spaced transverse loops adapted to singly receive the handles of tooth brushes, the heads of which project beyond one side of the belt, means for operating said belt, a flange projecting inwardly from one wall of the casing and arranged to be 60 successively engaged by the heads of the brushes, incident to the operation of the belt, a second right angularly disposed flange projecting inwardly of the casing and forming a pocket with the first mentioned flange to accommodate the 65 heads of said brushes, the forming of said flanges resulting in a finger receiving opening in a corner in the casing through which said heads are grasped for removal from the casing, and means carried by said second mentioned flange to prevent inward movement of the brush as it is being 70 grasped for removal.

BYRON A. BABEL.
